UNITED STATES PATENT OFFICE.

MILO L. DECKER, OF MAXWELL, NEBRASKA.

NUT-LOCK.

No. 923,251.

Specification of Letters Patent.

Patented June 1, 1909.

Application filed March 20, 1909. Serial No. 484,821.

To all whom it may concern:

Be it known that I, MILO L. DECKER, a citizen of the United States, residing at Maxwell, in the county of Lincoln and State of Nebraska, have invented certain new and useful Improvements in Nut-Locks; and I do hereby declare the following to be a full, clear, and exact description of the invention, such as will enable others skilled in the art 10 to which it appertains to make and use the same, reference being had to the accompanying drawings, and to the letters of reference marked thereon, which form a part of this specification.

15 This invention relates to new and useful improvements in nut locks and comprises various details of construction, combinations and arrangements of parts which will be hereinafter fully described and then specifically defined in the appended claim.

20 My invention is illustrated in the accompanying drawings, in which:—

Figure 1 is a perspective view of the invention showing a lock applied to a nut upon a bolt. Fig. 2 is a detail of one end of the bolt. Fig. 3 is an enlarged perspective view showing the lock applied to the nut, and Fig. 4 is a sectional view. Fig. 5 is an end view of the nut and pawl mounted thereon.

25 Reference now being had to the details of the drawings by letter, A designates a headed bolt having a threaded portion with a series of grooves B formed longitudinally therein, and D designates a nut mounted upon the threaded portion of the bolt, said nut having a threaded bore as usual and a recess E formed in the inner surface thereof.

30 F designates a pawl having a laterally projecting lug E' which is adapted to swing 40 into said recess and a portion of said lug projects within the bore of the nut and is adapted to engage one or another of the grooves in the bolt. Said pawl is pivotally connected to one end of the spring G which 45 in turn is fastened to one end of the nut and

said spring is adapted to hold the pawl frictionally and serves to retain the pawl in a locked relation after the latter is swung into a groove.

In applying the nut, it is fitted upon the 50 threaded portion of the bolt in the usual manner and, when it is desired to lock the nut, the pawl is swung upon its pivot so that the laterally projecting portion of the lug thereon will engage a groove in the bolt. 55 The spring bears with sufficient frictional force against the pawl to hold the same in its locked relation. A knob or headed pin K projects from the free end of the pawl and affords means for throwing the same in one 60 direction or the other as may be desired.

From the foregoing, it will be noted that by the provision of a nut lock as shown and described a simple and efficient means is afforded whereby a nut may be securely 65 held from loosening when adjusted upon a bolt and so arranged that the nut may be easily and quickly removed when desired.

What I claim to be new is:—

A nut lock comprising a bolt having a 70 threaded portion with grooves formed longitudinally therein and transversely across said threaded portion, a threaded nut fitted to said bolt, a spring fastened at one end to the end of said nut, a curved pawl pivotally 75 connected to said spring and adapted to be held by the latter frictionally against the end of the nut, a lug projecting from the inner concaved edge of said pawl and extending laterally and adapted to engage one or 80 another of the grooves in the bolt, and a knob upon the free swinging end of said pawl, as shown and described.

In testimony whereof I hereunto affix my signature in the presence of two witnesses. 85

MILO L. DECKER.
